United States Patent Office

Des. 206,966
Patented Feb. 14, 1967

206,966

JAR

Richard L. Weckman, Perrysburg, Ohio, assignor to Owens-Illinois, Inc., Toledo, Ohio, a corporation of Ohio

Filed May 23, 1966, Ser. No. 2,393

Term of patent 14 years

(Cl. D58—25)

FIG. 1

FIG. 2

FIG. 1 is a front elevational view of a jar, showing my new design.

FIG. 2 is a top plan view thereof.

FIG. 3 is a sectional view taken through line 3—3 of FIG. 1.

The back is a mirror image of the front.

The characteristic features of this design reside in the configuration shown in full lines on the drawing.

I claim:

The ornamental design for a jar, substantially as shown and described.
